FOLDING BABY CARRIAGE

Severine Hendrickson, Templeton, and Selim A. Fred, Gardner, Mass., assignors to Heywood-Wakefield Company, Gardner, Mass., a corporation of Massachusetts

Application November 13, 1939, Serial No. 304,098

10 Claims. (Cl. 280—41)

The present invention relates to baby carriages and particularly to a carriage of the collapsible type, which, by folding of the carriage body and supporting frame, may be stored in a small space.

In prior devices of this character, it has been desirable to provide for a slight resiliency in the supporting structure, so that the carriage body may be resiliently supported. Where resiliency has been obtained in the supporting structure, there has invariably been a sacrifice in the stability of the carriage or a sacrifice in the compact foldability thereof. The principal object of the present invention is to provide a supporting structure and carriage body capable of collapsing to a relatively small dimension and so arranged that the carriage body may be somewhat resiliently supported without sacrificing any steadiness of the carriage.

A further feature of the invention resides in the mounting of a brake structure so that it will not interfere in any way with the compact collapsing of the carriage, but which may be readily engaged or disengaged as desired. The invention also contemplates a more secure suspension of the carriage body from the supporting frame for greater stability.

Other and further objects and advantages of the invention will more fully appear from the following detailed description taken in connection with the accompanying drawings, in which—

Fig. 1 is a side elevation of the carriage embodying the invention.

Fig. 2 is a fragmentary side elevation on a larger scale of one of the latches which holds the carriage in extended position, looking in the direction of the arrow 2.

Fig. 3 is a sectional view through the latch along the line 3—3 of Fig. 1.

Fig. 4 is a view of a part of the under carriage looking in the direction of the arrow 4—4 of Fig. 1.

Fig. 5 is a fragmentary view looking in the direction of the arrow 5 of Fig. 1.

Fig. 6 is a plan view of the carriage.

Fig. 7 is a side view of the brake structure.

With reference first to Fig. 6, the carriage body has a supporting frame comprising a pair of spaced side elements 1 extending the length of the body and to which is pivotally mounted a U-shaped end element 2. The ends of the latter are pivoted to the elements 1 between the ends thereof by suitable pins 2a. The side walls 3 of the carriage body are of a flexible material and are suspended from the elements 1 and 2. The

carriage body has a bottom wall 4 to which the lower edges of the side walls are connected.

The carriage body is mounted on a supporting frame which is arranged to be extended to permit use of the carriage, as in Fig. 1, or to be collapsed, so that the carriage will occupy very little space when not in use. Referring to Fig. 1, the supporting frame embodies front and rear axles 5 and 6 on the opposite ends of each of which are positioned wheels 7. Reaches 8 extend between the front and rear axles to maintain a suitable spacing therebetween, and these reaches are connected to the axles by clips 9. The reaches 8 are somewhat resilient for a purpose which will hereinafter appear.

The supporting frame on each side of the carriage body is identical, and only the structure visible in Fig. 1 will be described. Forwardly of the front axle 5 and rearwardly of the rear axle 6 each reach 8 has depending lugs 10 and 10a rigidly attached thereto. To the lower end of forward lug 10 is pivotally connected, as by a pin 11, a link 12, and the free end of the link 12 is connected to the lower end of one arm 13 of the pair of side arms 13 and 14 by which the carriage body is supported. A similar pair of side arms is located on the opposite side of the body. A link 12a on the lug 10a has its opposite end connected to the other side arm 14. The side arms 13 and 14 cross each other and are pivotally connected substantially centrally thereof by a pivot pin 15. The arm 14 extending upwardly from adjacent the rear axle is pivotally connected at the top end to the side element 1 of the frame by a pin 14a. The other side arm 13 has its upper end pivotally connected as by a pin 13a to the lower end of the handle element 16.

Since the reaches 8 are resilient, as above stated, and since the supporting frames for the carriage body are mounted on the reaches at points spaced from the axles, it is obvious that the reaches will spring under the weight of the carriage body. In this way irregularities in the surface over which the carriage is wheeled are not communicated to the carriage body, but are absorbed by the resiliency of the reaches. It will be further noted that the link 12 extends rearwardly beneath the axle 5 and the reach 12a extends forwardly beneath the axle 6. Thus, as the links are rocked about the pivot pins by which they are connected to the lugs 10 and 10a on the reaches, they may engage the axles and limit undesirable endwise rocking of the carriage.

The handle element 16, as shown in Fig. 6, is substantially U-shaped and the depending arms

thereof are pivotally connected by pins 16a to the ends of the side elements 1, the pins 16a engaging the handle element above the extreme lower ends thereof. The lower ends of the depending arms of the handle element are connected by the pins 13a of the opposite side arms 13 at points spaced from the pins 16a. A latch 18 holds the portion of the handle element on each side of the carriage body in alignment with the side arm 13, as shown in Fig. 1.

With reference to Fig. 3, the latch, also shown in Fig. 2, is U-shaped in cross section with the arms of the U long enough to extend over and engage with the lower end of the handle element and also the side arm 13 pivotally connected thereto where the element and arm overlap. The latch is rockable on the same pin 13a that holds the side arm to the depending end of the handle. A spring 20 surrounding the pin 13a holds the latch against the face of the handle element and in the operative position of Fig. 2. The upper end or handle portion 18a of the latch is offset from the depending end of the handle, as shown in Fig. 2, so that the latch may be disengaged by an inward pressure on the upper end of the latch.

For more stability in the carriage, the pairs of side arms 13 and 14 on opposite sides of the carriage are connected together below the carriage bottom by a connecting rod 21, Fig. 4, the opposite ends of which are bent downwardly and secured to the side arms by the opposite pivot pins 15. Between the ends of this connecting rod is a depending lug 22 to which are pivoted, by a pin 23, the upper ends of downwardly diverging arms 24 and 24a connected at their lower ends to the short links 12 to which the side arms 13 are connected, the same pivot pin serving for both arms 13 and 24.

For a more rigid support of the carriage body without interfering with the collapsibility of the carriage, the bottom of the carriage has transverse bars 25 and 26 secured thereto, with the ends of the bars extending beyond the side edges of the carriage body and having upwardly extending integral lugs thereon. The lug on each end of the bar 25 is connected by a link 27 to the side arm 14, and the lug on each end of the bar 26 is connected by a pair of pivoted links 28 and 29 to the same side arm 14. Thus as the carriage is folded, the bottom of the carriage body may move toward the side elements 1 thereof, but upon opening of the carriage for use, these links 27, 28 and 29 will support the carriage bottom very securely. The pivoted link 28 projects beyond the upwardly extending lug on the bar 26 and engages with said bar to prevent the links 28 and 29 from straightening beyond the position shown, and thereby preventing collapse of the carriage.

The brake mechanism consists of a transverse bar 30 having depending portions 30a which are pivoted to lugs 31 on the reaches. The depending portions of the bar have laterally extending ends 30b in a position to engage with the rear wheels of the vehicle when the central portion of the bar is moved forwardly. The bar 30 has pivoted thereto a rearwardly extending arm 32 having a laterally extending end portion 33 which is in a position to be engaged by the foot of a person standing in back of the carriage. To the arm 32 is pivoted an arm 34 which is also pivoted on the rear axle 5. The arm 32 is curved as shown in Fig. 1, so that when the rearward end thereof is depressed, the pivot point of the arm 75

34 on the axle, the pivotal connection of the arms 32 and 34 and the pivot point of the arm 32 on the bar 30 may move into alignment and thereby prevent accidental release of the brake until downward pressure is exerted on the laterally extending end of the arm 34.

We claim,

1. A supporting frame for carriage bodies, comprising front and rear axles, reaches extending between said axles and holding them in spaced relation, a pair of pivotally connected side arms on each side of the carriage body, the upper ends of said arms being adapted to be connected to the carriage body, and rigid links connecting the lower ends of the arms of each pair to one of the reaches at points spaced from the axles, said reaches being resilient so that the carriage body is resiliently mounted.

2. A supporting frame for carriage bodies, comprising front and rear axles, a pair of reaches extending between the axles for holding them in spaced relation, a pair of pivotally connected side arms on each side of the carriage body, and a link connecting the lower end of one of the arms of each pair to one of the reaches at a point spaced from the axles, said reaches being resilient so that the link is resiliently mounted with respect to the axles.

3. A supporting frame for carriage bodies, comprising front and rear axles, a pair of reaches extending between the axles for holding them in spaced relation, a pair of pivotally connected side arms on each side of the carriage body, the arms of each pair diverging from the pivotal connection to points adjacent the front and rear axles respectively, a link pivoted to the lower end of each arm of each pair, the links for each pair of arms being pivoted to one of the reaches at points spaced from the adjacent axles at least the part of the reaches between the axles and the connections of the links thereto being resilient so that the carriage body is resiliently supported with respect to the axles.

4. A supporting frame for carriage bodies, comprising front and rear axles, a pair of reaches extending between the axles for holding them in spaced relation, a pair of pivotally connected side arms on each side of the carriage body, said reaches extending beyond the axles, a rigid link pivotally mounted on each end of each reach and projecting beneath the adjacent axle, the free ends of the links on each of the reaches being connected to the lower ends of the side arms of the pair of side arms on the same side of the carriage body at least the part of the reaches between the axles and the connections of the links thereto being resilient so that the carriage body is resiliently supported with respect to the axles.

5. A supporting frame for carriage bodies, comprising front and rear axles, a resilient reach extending between said axles, a pair of pivotally connected side arms having their upper ends connected to the body, a rigid link pivoted to the lower end of each arm, said links being pivoted to the reach at points spaced from the axles, the resiliency of the reach providing for a relative movement of the pivotal connection of the links with respect to the axles and thereby providing a resilient support for the carriage body.

6. A supporting frame for carriage bodies, comprising front and rear axles, a resilient reach extending between said axles, a pair of pivotally connected side arms having their upper ends connected to the body, and a pair of links pivoted

to the reach at points spaced from the axles, said links being pivotally connected to the lower ends of the pair of side arms, the resiliency of the reach providing for a relative movement of the pivotal connection of the links with respect to the axles and thereby providing a resilient support for the carriage body.

7. A supporting frame for carriage bodies, comprising front and rear axles, a resilient reach extending between said axles, a pair of pivotally connected side arms having their upper ends connected to the body, and a pair of links pivoted to the reach at points forwardly and rearwardly of the front and rear axles respectively, said links extending beneath the adjacent axles, the lower ends of said arms being pivotally connected to the links, the resiliency of the reach providing for a relative movement of the pivotal connection of the links with respect to the axles and thereby providing a resilient support for the carriage body.

8. In a supporting frame for carriage bodies, the latter having a rigid supporting structure including opposite side members, said frame including a pair of side arms, the upper end of one of the side arms being pivotally connected to one of said side members, a handle pivoted to said side member, a pivot pin connecting said handle to the other side arm at a point spaced from the connection of the handle to the side member, and a latch for holding said handle and said other side arm in extended relation, said latch being mounted for rocking movement on said pivot pin, and a spring for normally holding said latch in operative position, said latch being U-shaped in cross section to extend over both the end of the handle and the end of the corresponding side arm to hold said handle and side arm against relative movement.

9. In a supporting frame for carriage bodies, the latter having a rigid supporting structure including opposite side members, said frame in-

cluding a pair of side arms, the upper end of one of the side arms being pivotally connected to one of said side members, a handle pivoted to said side member, a pivot pin connecting said handle to the other side arm at a point spaced from the connection of the handle to the side member, and a latch for holding said handle and said other side arm in extended relation, said latch being mounted for rocking movement on said pivot pin, and a spring for normally holding said latch in operative position, said latch being U-shaped in cross section to extend over both the end of the handle and the end of the corresponding side arm to hold said handle and side arm against relative movement, one end of the latch being offset to extend parallel to and in spaced relation to the handle to provide for release of the latch by movement of said end of the latch toward the handle.

10. In a supporting frame for carriage bodies, front and rear axles, a pair of resilient reaches extending between the axles for holding them in spaced relation, a pair of pivotally connected side arms on each side of the carriage body, a link pivotally mounted on each end of each reach and projecting inwardly of the supporting frame and beneath the adjacent axle, the free ends of the links on each of the reaches being connected to the lower ends of the side arms of the pair of side arms on the same side of the carriage body, said links, by engagement with the axle as the carriage is rocked, controlling the relative movement of the body with respect to the axles, said reaches being resilient at least in the portions between the axles and the connections of the links thereto, whereby the connection for the link is movable with respect to the adjacent axle to a limited degree so that the carriage body is resiliently supported with respect to the axles.
